ing the overlapped ends of the foot boards, and means connected with another one of said runs and with the foot boards beyond the overlapped ends of the foot boards and relatively bracing said supporting structure and the foot boards and holding the latter in place upon the first mentioned rung.

7. In a scaffold of the class described, a supporting structure, foot boards mounted thereon and having relatively adjacent overlapped ends, the supporting structure including side members and a rung extending

between the side members and supporting the overlapped ends of the foot boards, means anchoring the said overlapping ends of the 15 foot boards to the said rung, a rung connecting the side members of the structure below the first mentioned rung, and brace arms connected with the last mentioned rung and extending upwardly at an angle therefrom and 20 connected at their upper ends with the said foot boards.

In testimony whereof I affix my signature.
ALFRED C. FARLEY.

UNITED STATES PATENT OFFICE.

EDWARD A. FIELD, OF CHICAGO, ILLINOIS, ASSIGNOR TO FIELD ENGINEERING CO., OF CHICAGO, ILLINOIS, A CORPORATION OF ILLINOIS.

OIL BURNER.

Application filed June 25, 1923. Serial No. 647,657.

This invention relates to improvements in oil burners.

The main objects of the invention are:

First, to provide an improved oil burner 5 which may be installed in furnaces and in other relations where desired which is very efficient.

Second, to provide an improved burner for the burning of heavy oils and distillate which 10 is substantially smokeless, there being comparatively little residue from the combustion when the proper amount of air is supplied.

Third, to provide an improved oil burner 15 which automatically cuts off the supply of fuel in the event of any considerable excess being supplied to the burner.

Fourth, to provide an improved oil burner having these advantages which may be quickly installed in furnaces of types now in quite 20 common use.

Further objects, and objects relating to structural details, will definitely appear from the detailed description to follow.

The objects of the invention are accomplished 25 by the devices and means described in the following specification. The invention is clearly defined and pointed out in the claims.

A structure which is a preferred embodiment 30 of the invention is clearly defined and illustrated in the accompanying drawing, forming a part of this application, in which:

Fig. I is a fragmentary side elevation of a hot air furnace having my improved oil 35 burner installed therein, the furnace being shown in conventional form and for the purpose of illustrating the manner of installation.

Fig. II is a detail vertical section on a line 40 corresponding to line 2—2 of Fig. III.

Fig. III is a horizontal section on a line corresponding to line 3—3 of Fig. II.

Fig. IV is a detail section through the vaporizing head on a line corresponding to 45 line 4—4 of Fig. II.

Fig. V is a fragmentary plan view of the fan removed from the spindle.

Fig. VI is a detail section on a line corresponding to line 6—6 of Fig. II.

In the drawing similar reference characters refer to similar parts throughout the several views and the sectional views are taken looking in the direction of the little arrows at the ends of the section lines.

Referring to the drawing, 1 represents the

furnace body and 2 the surrounding hot air casing. 3 represents the furnace grates and 4 the ashpit door having the regulating damper 5. The smoke flue is provided with a damper 6. These parts are shown conventionally and for the purpose of showing the installation of my improvements.

My improved burner comprises a body which in the embodiment illustrated is formed of an outer burner member 7, an inner burner member 8 and an intermediate burner member 9. These burner members are cylindrical and disposed in concentric spaced relation, providing an air passage 10 open at the bottom of the outer burner member and delivering to the bottom of the combustion chamber 11.

The inner burner member is provided with an outwardly curved flange 12 at its upper end, the edge of the flange seating on the top of the outer burner member 7, thus providing an air passage having an outer upward reach or portion and an inner downward reach or portion, the downward reach or portion surrounding the combustion chamber so that the air is heated on its passage to the combustion chamber.

The intermediate burner member is provided with a bottom 13 having central air inlets 14 surrounded by the upwardly projecting tubular part 15. The bottom has cleanout openings 16 which are normally closed by the cleanout damper 17 which has registering openings 18 therein. A connection 19 is provided for manipulating the damper 17. The bottom is conformed to provide a trough 20 to which the drain pipe 21 is connected, so that in the event of any considerable surplus of fuel it is drained off through this drain connection 21. This drain connection 21 delivers to a drain receptacle 22 having a float 23 therein for controlling the valve 24 in the fuel supply pipe 25 which leads from the fuel supply reservoir 26. A pair of nozzles 27 is connected to the pipe 25 to project through the walls of the burner body.

These nozzles have downwardly directed delivery orifices 28. The spindle 29 is supported by the self-lubricating bearing 30 carried by the arm 31 and by the end cross bearing 32 within the bearing member 33 which is disposed centrally of the air inlets 14 so that this bottom bearing is cooled by the air passing around the same. The bearing member 32 is chambered to receive the lubricant, being connected by the pipe 34 to

85

90

100

105

110

a suitable lubricant supply or the pipe may be extended so that the lubricant may be introduced thereto as required.

For convenience in assembling the inner body member 8 is provided with a slot 35 which permits its being dropped over the arm 31, the arm having a depending closure 36 for this slot. The arm is secured by means of the screw 37 arranged through the outer 10 and intermediate body members.

The spindle is driven by the impelling fan 38 which is disposed within the combustion chamber adjacent the lower end thereof to receive the impact of the air entering from the 15 passage 10 and also that entering through the inlets 14. The fan is provided with a hub portion 39 which is notched at its lower end to engage the transverse pin 40 on the spindle. This provides a convenient means for assembling and disassembling.

The atomizing head, designated generally by the numeral 41, is mounted on the spindle in coacting relation to the fuel nozzles. This atomizing head comprises a top deflector plate 25 42 which is disposed in a plane above the nozzles but adjacent thereto. The annular distributing or atomizing plate 43 is disposed below the nozzle so that the fuel is discharged thereto. A fan 44 is provided having blades 30 46 projecting beyond the periphery of the plate 43, the purpose being to assist in breaking up and atomizing fuel and also to assist in driving the spindle. The head is open at the bottom within the distributing plate and 35 has side delivery openings 45.

With this arrangement of parts the fuel is effectively atomized and very efficient and complete combustion is secured. The fuel feed pipe 25 is provided with a fuel regulating 40 valve 24. The dampers 5 and 6 of the furnace regulate the supply of air.

In the event of failure of ignition or the temporary stoppage of the flow of oil such as would extinguish the flame, the flow being 45 renewed is collected by the trough 20 delivering to the drain receptacle 21 and actuates the float 23 to close the valve 24, thereby stopping the flow of fuel.

The cleanout damper is provided in the 50 event that there should be a collection of ash or residue.

The structure is readily disassembled should occasion require by the removal of the nozzles which may be pulled out by swinging 55 the couplings 47 to one side. The head may then be lifted off as it is supported by the pin 48 engaging a notch in the upper end of the spindle.

My improved burner is very efficient, is 60 readily installed and requires very little attention in use. It is very effective in the consumption of heavy oils and distillate.

I have illustrated and described my improvements in an embodiment which I have 65 found very practical in use. I have not at-

tempted to illustrate or describe certain embodiments or adaptations which I contemplate as I believe the disclosure made will enable those skilled in the art to which this invention relates to embody or adapt the same 70 as may be desired.

Having thus described the invention what is claimed and desired to secure by Letters Patent, is:

1. In an oil burner, the combination of 75 cylindrical outer, inner and intermediate burner members disposed in spaced concentric relation, the outer member being open at the bottom, the inner member having an outwardly curved flange at its upper end resting on the top of the outer member, the intermediate member having a bottom spaced from the lower end of said inner member whereby a return air passage is provided delivering into the bottom of the inner member, said bottom 80 having a central air inlet surrounded by a collar and being conformed to provide a trough and having cleanout openings therein, a drain connection for said trough, a damper for said openings, a spindle disposed centrally 85 of said inner member, an impelling fan disposed on said spindle adjacent the lower end of said inner burner member, fuel delivery nozzles projecting into said inner burner member, and an atomizing head mounted on 90 said spindle in coacting relation to said nozzles.

2. In an oil burner, the combination of 100 cylindrical outer, inner and intermediate burner members disposed in spaced concentric relation, the outer member being open at the bottom, the inner member having an outwardly curved flange at its upper end resting on the top of the outer member, the intermediate member having a bottom spaced from the lower end of said inner member whereby 105 a return air passage is provided delivering into the bottom of the inner member, said bottom having a central air inlet, a spindle disposed centrally of said inner member, an impelling fan disposed on said spindle adjacent the lower end of said inner burner member, fuel delivery nozzles projecting into said inner burner member, and an atomizing head 110 mounted on said spindle in coacting relation to said nozzles.

3. In an oil burner, the combination of 115 cylindrical outer, inner and intermediate burner members disposed in spaced concentric relation, the outer member being open at the bottom, the inner member having an outwardly curved flange at its upper end resting on the top of the outer member, the intermediate member having a bottom spaced from the lower end of said inner member whereby 120 a return air passage is provided delivering into the bottom of the inner member, said bottom having a central air inlet surrounded by a collar and being conformed to provide a trough and having cleanout openings therein, 125

a drain connection for said trough, a damper for said openings, a spindle disposed centrally of said inner member, an end bearing therefor disposed centrally within said air inlet, a lubricant connection for said bearing, a top bearing for said spindle, a supporting arm therefor projecting inwardly from said intermediate burner member, said inner burner member being vertically slotted to receive 10 said arm, the arm being provided with a closure for said slot, an impelling fan disposed on said spindle adjacent the lower end of said inner burner member, fuel delivery nozzles projecting into said inner burner member, 15 and an atomizing head mounted on said spindle in coaxing relation to said nozzles.

4. In an oil burner, the combination of cylindrical outer, inner and intermediate burner members disposed in spaced concentric relation, the outer member being open at the bottom, the inner member having an outwardly curved flange at its upper end resting on the 20 top of the outer member, the intermediate member having a bottom spaced from the lower end of said inner member whereby a return air passage is provided delivering into the bottom of the inner member, said bottom having a central air inlet, a spindle disposed centrally of said inner member, an impelling 25 fan disposed on said spindle adjacent the lower end of said inner burner member, fuel delivery nozzles projecting into said inner burner member to deliver downwardly therein, an atomizing head mounted on said spindle and comprising a top deflector plate disposed in a plane above the nozzles, and an annular deflector plate disposed below said nozzles, said head being provided with fan blades 30 at the periphery of said atomizing plate and having a bottom opening within said atomizing plate and side openings below said deflector plate.

5. In an oil burner, the combination of cylindrical outer, inner and intermediate burner members disposed in spaced concentric relation, the outer and inner members being open at the bottom, the inner member having an outwardly curved flange at its upper end resting on the top of the outer member, the intermediate member having a bottom spaced 45 from the lower end of said inner member whereby a return air passage is provided delivering into the bottom of the inner member, said bottom having cleanout openings therein, a damper for said openings, a spindle disposed centrally of said inner member, an atomizing head mounted on said spindle within said inner member, an impelling fan mounted on said spindle below said atomizing head and within and adjacent to the lower end of said inner member whereby it is driven by the natural draft of air induced through said inner member by the combustion within the burner, and a fuel nozzle delivering to said 50 atomizing head.

6. In an oil burner, the combination of cylindrical outer, inner and intermediate burner members disposed in spaced concentric relation, the outer and inner members being open at the bottom, the inner member having 70 an outwardly curved flange at its upper end resting on the top of the outer member, the intermediate member having a bottom spaced from the lower end of said inner member whereby a return air passage is provided delivering into the bottom of said inner member, said bottom being conformed to provide a trough, the trough having clean-out openings therein, a damper for said clean-out openings, a drain connection for said trough, 75 a spindle disposed vertically and centrally of said inner member, an atomizing head mounted on said spindle within said inner member, and a spindle driving fan mounted on said spindle below said atomizing head to be subject to and driven by the draft of air created by the combustion.

7. In an oil burner, the combination of a burner body having a central combustion chamber open at the top, the walls of said body being disposed to provide an annular air passage comprising an outer up-draft portion open at the bottom of the body and an inner down-draft portion delivering to the lower end of the combustion chamber, the wall of the combustion chamber constituting the inner 90 wall of the down-draft portion of said air passage, said body having a bottom provided with a central air inlet, a spindle disposed centrally of said combustion chamber, a bearing for said spindle disposed centrally of said air inlet in said bottom, a lubricant connection for said bearing, an impelling fan disposed on said spindle adjacent the lower end of said combustion chamber, an atomizing head on 95 said spindle, and a fuel nozzle delivering to said atomizing head.

8. In an oil burner, the combination of a burner body having a central combustion chamber open at the top and bottom, the walls of said body being disposed to provide an annular air passage comprising an outer up-draft portion open at the bottom of the body and an inner down-draft portion delivering to the lower end of the combustion chamber, the wall of the combustion chamber constituting the inner wall of the down-draft portion of said air passage, a spindle disposed centrally of said combustion chamber, an impelling fan disposed on said spindle adjacent the lower 110 end of said combustion chamber so that it is driven by the current of air induced through said combustion chamber by the combustion of fuel therein, an atomizing head mounted on said spindle within said combustion chamber so that the air passing through said combustion chamber passes said atomizing head, and a fuel nozzle delivering to said atomizing head.

9. In an oil burner, the combination of a 130
